(57) **CLAIM**

The ornamental design for an IP desktop phone, as shown and described.

DESCRIPTION

FIG. 1 is a front view of an IP desktop phone showing my new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a perspective view thereof; and,

FIG. 8 is another perspective view thereof with the phone receiver illustrated in broken lines.

The broken lines showing the phone receiver depict environmental subject matter only and form no part of the claim, while all other broken lines in the drawings depict portions of the IP desktop phone that form no part of the claimed design.
